UNITED STATES PATENT OFFICE.

WYLIE GEMMEL WILSON, OF ELIZABETH, NEW JERSEY, ASSIGNOR, BY MESNE ASSIGNMENTS, TO EVERLASTING VALVE COMPANY, A CORPORATION OF NEW JERSEY.

MACHINE FOR MIXING AND PLACING CONCRETE AND OTHER MATERIAL.

1,290,459.

Specification of Letters Patent.

Patented Jan. 7, 1919.

Application filed May 4, 1917. Serial No. 168,405.

To all whom it may concern:

Be it known that I, WYLIE GEMMEL WILSON, a subject of the King of Great Britain, residing at Elizabeth, in the county of Union and State of New Jersey, have invented certain new and useful Improvements in Machines for Mixing and Placing Concrete and other Material, of which the following is a specification.

10 The main object of the invention is to effect a new and increased rapidity of the discharge of mixed concrete-forming aggregates or other material from a compressed-air-containing chamber.

15 In the accompanying drawings forming a part hereof and illustrating the principle of my invention in the best mode now known to me of applying that principle,

20 Figure 1 is a vertical central sectional elevation of my new concrete mixing and placing machine, through the axis of rotation of its drum; and

25 Fig. 2 is an end view of an adjustable shield for covering the inward intake end of the material-discharge pipe during the mixing operation.

30 Referring to the drawings, the revoluble drum 1 is provided with interior mixing, lifting and spilling blades 2 and is rotated in a well-known way by well-known means. The blades 2 are carried by the interior wall of the drum and in the preferred form as shown are each scoop-shaped, being of approximately triangular shape in plan view. 35 Each end portion of a blade is inclined toward its mid-section, and its apical portion 2^a is at the front edge of the mid-section. As these scoop-shaped blades successively come to the top of the drum in its rotation 40 for discharge of the mixed material after the aggregates have been properly mixed by previous rotation of the drum, they severally discharge *seriatim* into the open up-standing end of the discharge pipe 3. This 45 upstanding end portion of the discharge pipe 3 curves downwardly to a horizontal portion of the pipe which is fixed tightly in a pair of collars 4 that are fixed in an annulus 5 which leads out of the drum.

50 55 through a central opening in its discharge end. Stuffing-box members 6 are used to form an air-tight connection of the annulus 5 in such central opening of the drum, the collars are fixed air-tightly in the annulus 55 around the pipe 3, and the assemblage of

the collars, annulus, discharge pipe and stuffing-box members is stationary and is in part supported by a strut 7 which is fixed at its upper end to the projecting end of the annulus 5 and fixed at its lower end by 60 its foot 8 to the frame base.

An air inlet pipe 9, assumed to lead from an air receiver of an air-compressing apparatus, and having a control valve 10, is air-tightly fixed in holes through the collars 4 65 with its inner discharge end open into the drum chamber and not into the discharge pipe 3.

During the mixing of the aggregates the open end of the discharge pipe within the 70 drum chamber is closed against admission into it of the mixed aggregates by means of a shield 11 which is fixed to the inner arm 12 of a horizontal rocker shaft 13 which is journaled in holes through collars 4 and 75 provided at its exterior end with a crank handle 14 by a movement of which the shield is rocked into or out of position above the open up-turned end of the discharge pipe 3. The upper sides of the shield are down- 80 wardly slanted so that material dropped on it by the blades during the mixing operation will not lodge thereon, but will slide off and drop to the bottom of the drum chamber wherein the aggregates are mixed by the 85 movement of the mixing, lifting and spilling blades, as usual.

The drum is shown provided with a central opening on its intake end as usual, and this opening is closed by a disk-shaped edge-wise-swinging door 15 provided with an exterior upper projecting hinge pin 16 which is journaled in an exterior projecting boss 17 of the drum end. A crank handle 18 fixed to the outward end of the hinge pin 16 90 serves for opening and closing the door the margin of which makes a suitably tight joint with the margin of the intake opening of the drum and when the door is in closed position.

95 The scoop shape of the mixing, lifting and spilling blades is not new with me, and various changes may be made in the form of my invention without departing from it.

100 105 The gland members 6, 6 rotate with the drum around the stationary annulus 5 as a bearing, one of the members being fixed to and projecting from the drum, and the other being connected therewith, as by a screw 6^a, in a known way.

110

A novel and very important mode of operation is involved in the described construction. The material discharge pipe 3 is shown of uniform diameter, its outwardly projecting end being constructed to be coupled with a pipe or flexible placing hose α in the usual way. Heretofore the desirable rapidity of discharge of the mixed concrete by compressed air has not been obtainable in practice for a variety of reasons, one of which is that at the greater bend of the material discharge pipe as at y the material appears usually to encounter undue skin friction with the inner wall of the discharge pipe; and generally speaking, and so far as I am aware, the compressed air used for effecting the discharge has tended either to wedge a conoidal mass or to force the outer walls of a mass of other shape against the inner wall of the discharge pipe, thereby hindering the requisite rapidity of discharge and very often resulting in non-discharge or an intermittent discharge of the concrete from the machine. It has been hitherto proposed to form a conoidal mass of the mixed aggregates in the discharge conduit, compacting the mass as a plug or wad by compressed-air pressure on its inward end, and then to move the wad or plug in more or less balanced pressure out of the discharge pipe. This mode of operation as above indicated results in forcing the soggy concrete mixture against the inner wall of the pipe to a considerable extent, and involves undue skin friction. Again, it has been proposed to drive a body of the mixed material out of a concrete-containing compartment by means of an air blast which pushes a charge of the mixture out of the compartment into a discharge pipe. And again, it has been proposed to introduce a blast of compressed air into the base of a discharge hopper and so entrain a charge of the wet mass on the principle of an injector and shoot it through a discharge pipe. The latter case often results in a bridging of the material above the compressed-air entraining current, and the air blast itself at the base portion of a hopper offers some resistance to the movement thereinto of the mixed aggregates. The chamber of the drum is filled with air under a greater pressure than the outside atmospheric pressure, and this air rushes from all directions within the drum into the upper or hopper end of the upstanding portion of the discharge pipe, and flows as a current out through the discharge pipe and into the placing hose or conduit α . The velocity of the escaping air current is greatest at the mouth of the upper receiving or hopper end of the discharge pipe, and as the blades successively reaching the upper portion of the drum severally spill a stream downward through the compressed-air volume in the drum

chamber, such stream first encounters the compressed-air current at the mouth or hopper or receiving end of the discharge pipe 3 where the compressed-air current has the greatest velocity, and at this moment of the first meeting of the gravitating material with the compressed-air current and subsequently, the compressed-air current instead of spreading or tending to spread and thereby force the material against the interior wall of the pipe 3, appears very clearly to form more or less of an air film between the exterior of the material and the interior wall of the pipe 3, cutting down the skin friction and particularly eliminating the resistance which this material generally has in passing the larger bend as at y . Bridging and clogging in the receiving end of the discharge pipe are prevented, and the material is by more or less intermixture with the compressed-air current conveyed, rather than caused to travel by a forcing pressure or by entrainment on the principle of an injector. The stream of material and the outflowing compressed-air current both move in the same direction, each at its highest velocity, and unite in the discharge pipe as a current and with a minimum diminution of the stream and current velocities. There is no impingement of the stream on the air current at an angle thereto, or vice versa, at the moment of entry of the material into the air current.

What I claim is:—

1. The combination of a drum having an inlet means for material and interior revolvable mixing, lifting and spilling blades, said drum having a bearing in one end, in combination with a bent discharge pipe which is tubular from end to end and which has within the drum chamber an upstanding tubular portion, the upper tubular end of which is open, adjacent and below the discharge end of a blade as the blade comes to the top of the drum, the discharge pipe within the drum chamber being closed to the admission of air except at its said upper open tubular end; and a compressed air supply pipe which discharges directly into the drum chamber.

2. The combination of a drum having an inlet means for material and interior revolvable mixing, lifting and spilling blades, said drum having a bearing in one end, in combination with a bent discharge pipe which is tubular from end to end and which has within the drum chamber an upstanding tubular portion, the upper tubular end of which is open, adjacent and below the discharge end of a blade as the blade comes to the top of the drum, the discharge pipe within the drum chamber being closed to the admission of air except at its said upper open tubular end; a compressed air supply pipe which discharges directly into the

drum chamber, said bearing being stationary and the discharge pipe and the compressed air supply pipe being mounted in said bearing; and a movable shield for the 5 upper open tubular end of the discharge pipe.

3. The combination of a drum having an inlet means for material and interior revoluble mixing, lifting and spilling blades, said 10 drum having a bearing in one end, in combination with a bent discharge pipe which is within the drum chamber an upstanding tubular portion, the upper tubular end of 15 which is open, adjacent and below the dis-

charge end of a blade as the blade comes to the top of the drum, the discharge pipe within the drum chamber being closed to the admission of air except at its said upper open tubular end; and a compressed air 20 supply pipe which discharges into the drum chamber, the blades severally having an apical stream discharging edge for direction of a stream into the open tubular adjacent end of the upstanding portion of the 25 discharge pipe.

In testimony whereof I have hereunto set my hand this 3rd day of May, 1917.

WYLIE GEMMEL WILSON.
